Amazon.com, KES Towel Racks for Bathrooms, Dec. 20, 2022, <https://www.amazon.com/KES-Bathroom-Standing-Stainless-BTH219-BZ/dp/B0BQMDD3NY/> (Year: 2022).*Primary Examiner — Nathan M Johnston(57) **CLAIM**

The ornamental design for a towel rack as shown and described.

DESCRIPTION

FIG. 1 is a front, right, and top perspective view of a towel rack with three hanging bars, showing my new design;
 FIG. 2 is a front elevational view thereof;
 FIG. 3 is a rear elevational view thereof;
 FIG. 4 is a left elevational view thereof;
 FIG. 5 is a right elevational view thereof;
 FIG. 6 is a top plan view thereof;
 FIG. 7 is a bottom plan view thereof;
 FIG. 8 is an enlarged view of the delineated region 8 in FIG. 1;

FIG. 9 is a front, right, and top perspective view of another towel rack with four hanging bars;
 FIG. 10 is a front elevational view thereof;
 FIG. 11 is a rear elevational view thereof;
 FIG. 12 is a left elevational view thereof;
 FIG. 13 is a right elevational view thereof;
 FIG. 14 is a top plan view thereof;
 FIG. 15 is a bottom plan view thereof; and,
 FIG. 16 is an enlarged view of the delineated region 16 in FIG. 9.

The broken lines in the drawings depict portions of the towel rack that form no part of the claimed design. The dot-dash broken lines in FIGS. 1, 8, 9, and 16 form no part of the claimed design and delineate portions of the claimed design that are shown on an enlarged scale in FIGS. 8 and 16.

1 Claim, 16 Drawing Sheets(56)
